UNITED STATES PATENT OFFICE

BURT A. PETERSON AND BROOKS MARCELLUS, OF ROCKFORD, ILLINOIS, ASSIGNORS TO
HOWARD D. COLMAN, OF ROCKFORD, ILLINOIS

DESIGN FOR A PORTABLE ELECTRIC FAN

Application filed November 14, 1930. Serial No. 37,659. Term of patent 14 years.

To all whom it may concern:

Be it known that we, BURT A. PETERSON and BROOKS MARCELLUS, citizens of the United States, residing at Rockford, in the county of Winnebago and State of Illinois, have invented a new, original, and ornamental Design for Portable Electric Fans, of which the following is a specification, reference being had to the accompanying drawings, forming part hereof.

Fig. 1 of the drawings is a front elevational view of an electric fan of our new design, the fan wheel and guard being omitted. Fig. 2 is a side elevational view of the same, the fan wheel and guard being shown in broken lines. Fig. 3 is a plan view.

The design is especially characterized by the use of a casing of generally circular contour having front and rear apertured walls with flat outer surfaces, the fan shaft projecting from the front face in offset relation to the axis of the casing, and the outer peripheral surface of the casing being interrupted at its lower side by a depending projection attached to the upper end of a supporting standard, substantially as shown.

We claim:

The ornamental design for a portable electric fan, substantially as shown and described.

BURT A. PETERSON.
BROOKS MARCELLUS.
